UNITED STATES PATENT OFFICE.

ALFRED L. EUSTICE, OF CHICAGO, ILLINOIS.

HOLDING MEANS FOR ELECTRIC FIXTURES.

Application filed May 10, 1922. Serial No. 559,762.

The present invention relates to holding means for electric fixtures.

In providing mountings for electric fixtures it is common practice to provide a switch which presents a plane surface substantially flush with the wall, floor or ceiling in which it is mounted, said switch being ordinarily termed a "wall outlet or receptacle." A mating switch member, termed a 10 plug, is also provided having parts projecting into and interfitting with the wall outlet for providing a more or less convenient electrical connection between the wall outlet and an electric fixture. In order to provide a 15 neat job, the electric fixture may be mounted flush with the surface carrying the wall outlet, which arrangement presents certain problems. Inasmuch as in many instances the electric fixtures are intended to be sold 20 to and mounted by persons who are not skilled artisans, it is desirable to reduce to a minimum the difficulties attendant to the job of mounting the fixtures and to provide a structure which, though readily 25 mounted or dismounted, will always maintain its proper position upon the surface upon which it is mounted.

An object of the present invention is to provide an electric fixture cooperating with 30 structure which is now in common use, said fixture having the advantage that it may be readily mounted by a person having a minimum of mechanical skill, will present a neat appearance, and will maintain itself in 35 proper position.

A further object is to provide an improvement which may be applied to electric fixtures now in common use whereby to simplify the mounting of said fixtures and to 40 improve their stability when mounted.

Further objects will appear as the description proceeds.

Referring to drawings—

Figure 1 represents in side elevation, parts 45 being broken away, one embodiment of the present invention applied to an electric side wall outlet or receptacle of well known construction;

Figures 2 and 3 are views in front elevation and side elevation respectively of the

wall outlet or receptacle illustrated in Figure 1;

Figures 4 and 5 are views in front elevation and side elevation respectively of an electric plug member adapted to be applied 55 to the wall outlet or receptacle shown in Figures 2 and 3;

Figure 6 is a view in front elevation, parts being broken away, showing an embodiment 60 of the present invention cooperating with the wall outlet or receptacle shown in Figures 2 and 3 and the plug member shown in Figures 4 and 5; and

Figure 7 is a view in side elevation, parts being broken away, illustrating a modified 65 embodiment of the present invention.

The numeral 10 indicates a wall outlet of well known construction having a face plate 11 adapted to be mounted substantially flush with a wall or other member providing a 70 substantially vertical flat surface. In the rear of the face plate 11 is the receptacle 12 containing certain mechanism which need not be described herein, providing terminals for electric wiring. The face of the receptacle 12 may be provided with a plurality of slots 13—13 for the reception of projecting tongues of the plug member. A plug member of well known construction is illustrated in Figures 4 and 5 and is indicated by the 80 numeral 14. Said plug member 14 has the projecting tongues 15—15 adapted to project into certain of the slots 13—13 of the wall receptacle 10. Said plug member 14 will be provided with binding post means whereby 85 connection may be made to some electric translating device such as an electric socket. The plug 14 is illustrated as being of the kind which is known in the art as an Elexit plug and need not be described in detail 90 herein, though it may be stated briefly that the rear portion of said device is provided with a pair of hook-shaped members 16—16 adapted to enter slots 17—17 of the face plate 10 and spring into locking engagement 95 with said face plate. When said hook-shaped members 16—16 are interlocked with the face plate 11, the plug member 14 is rigidly mounted upon the receptacle 10 and will not come loose except upon the actual 100

tion of certain operating mechanism. The operating mechanism, which is well known to those skilled in the art, includes the spring-controlled member 16^a which may be moved to release the lock behind the lower hook-shaped member 16, whereby the plug 14 may be removed from the wall face plate 10. The plug 14 is provided with the spring gripping member 18 having the lip 19, which lip 19 is adapted to yieldingly engage part of a wall fixture to hold the same in position on a wall.

The plug member 14 as commonly provided has a pair of substantially parallel side walls 20. According to the present invention, an electric fixture, which is intended to be mounted flush with the same surface which carries the face plate 11, will be provided with a fitting comprising a member adapted to engage the top wall 21 of said plug member 14 and a pair of members adapted to embrace said plug member 14 along the two side walls 20, and adapted to also engage behind the lip 19.

Referring particularly to Figures 1 and 6, a style of electric fixture is illustrated having a relatively shallow canopy 22. Fastened on the inside of said canopy, as for instance by means of solder, is the fitting 23 having the cross bar 24 and the two depending members 25—25, which depending members 25—25 will have their inside edges preferably arranged in parallel vertically placed lines 26—26. The depending members 25—25 will embrace the side walls 20—20 of plug member 14 and the cross bar 24 will rest upon the upper wall of said plug member 14.

The canopy 22 connects with the tube 27 which may lead to an electric light socket. Electric wires 27^a may extend through the tube 27 from the electric light socket and they may be connected to the plug member 14 under the canopy 22. In accordance with usual electric wiring practice, there may be sufficient length of wire to permit the ready inserting of the plug member 14 into the receptacle 10, after which the electric fixture may be placed with the base of the canopy 22 substantially flush with the wall and with the depending members 25—25 in substantial alignment with the side walls 20—20 of the plug member 14. A simple downward movement of the fixture will cause the depending members 25—25 to embrace the sides of the plug member 14, the cross bar 24 resting upon the top wall 21 of said plug member 14. Skewing effect will be prevented by reason of the engagement of the depending members 25—25 with the sides of the plug member 14. The member 14 has portions 28—28 projecting laterally from each side thereof, which portions are adapted to engage depending portions 25—25, whereby the canopy 22 is held

against a skewing movement in a plane perpendicular to the wall on which it is mounted.

The modification illustrated in Figure 7 shows a very popular type of electric fixture and one which under ordinary practice presents difficulties to inexperienced workers when said inexperienced workers attempt to mount said fixtures. According to the embodiment illustrated in Figure 7, a piece of pipe 29 is employed which serves as a conduit for electric wires leading to the electric socket 30. Said pipe 29 is encased within ornamental tubing 31 which carries the relatively deep canopy 32. According to the present invention, a fitting 33 is provided having a depending leg having a screw-threaded hole therein, whereby said leg may have screw-threaded engagement with the end of the pipe 29. A nut 34 also engages the end of the pipe 29 and serves as a lock nut to hold the fitting 33 in tight engagement with the end of the ornamental tubing 31. It will be understood, of course, that if preferred the fitting 33 need not be screw-threaded, the parts being held together in any other preferred way. As in the embodiment illustrated in Figures 1 and 6, the fitting is provided with the cross bar 23', which may be united by means of solder or riveting to the canopy 32 and is provided with depending members adapted to embrace the two sides of the plug member 14. As described above, in connection with Figures 1 and 6, the electric wires leading to the socket 30 will be of sufficient length to permit the convenient application of the plug member 14 to the wall receptacle 10. After said plug member 14 has been placed in position relative to said wall receptacle the electric fixture may be conveniently mounted upon the member 14 flush with the wall by a simple downward movement of said fixture.

The ordinary awkward expedient of sliding the canopy 32 along the tubing 31 is rendered unnecessary, whereby it is unnecessary to provide a sliding connection between said members or locking means for controlling said sliding connection. A locking screw 35 is shown in Figure 7 inasmuch as said figure discloses a canopy of common construction. According to the present invention, however, which removes the necessity for a sliding connection between canopy 32 and tubing 31, the locking screw 35 is unnecessary.

The present invention has the advantages that it provides structure which may be conveniently operated by unskilled persons and will remain in proper position as long as it is in use. The fixture is as readily removed as it is mounted and provides a convenient fool-proof construction which may be provided at a minimum of expense.

The illustrated embodiments have been

chosen merely for the purpose of illustration and should not be considered in a limiting sense. Many modifications will occur to those skilled in the art. It is intended 5 in this patent to cover all such modifications that fall within the scope of the invention as defined by the appended claims.

I claim:

1. In combination, a wall receptacle, a 10 plug member adapted to be connected thereto, said plug member being non-rotatable and having parallel side walls, and an electric fixture having a fitting comprising a member for resting upon the top of said plug 15 member and having members for embracing the sides of said plug member.
2. In combination, a wall receptacle, a 20 plug adapted to be connected thereto, said plug being non-rotatable and having parallel side walls and an electric fixture 25 having a fitting comprising a member for resting upon the top of said plug and having members for embracing said side walls of said plug, said plug being provided with means projecting laterally therefrom in spaced relationship with said wall receptacle and providing an abutment for said fitting in a direction away from said wall 30 receptacle.

Signed at Chicago, Illinois, this 5th day of May, 1922.

ALFRED L. EUSTICE.
